UNITED STATES PATENT OFFICE.

ALFRED L. STEVENS, OF CHICAGO, ILLINOIS.

MEANS FOR SUPPORTING RAILWAY-RAILS.

1,106,421.

Specification of Letters Patent.

Patented Aug. 11, 1914.

Application filed May 10, 1913. Serial No. 766,670.

To all whom it may concern:

Be it known that I, ALFRED L. STEVENS, a citizen of the United States, residing at Chicago, in the county of Cook and State of Illinois, have invented certain new and useful Improvements in Means for Supporting Railway-Rails, of which the following is a specification.

My invention relates to improvements in means for supporting railway rails.

Some of the objects of my invention are to provide simple, efficient, durable and relatively inexpensive means for supporting the meeting ends of railway rails, to preserve constant the relative gage distance or separation of the rails and to maintain in proper, horizontal alignment the tread surfaces thereof.

Other and further objects of my invention will become readily apparent to persons skilled in the art, from a consideration of the following description when taken in connection with the drawings wherein;—

Figure 1 is a plan view of a section of railway track built by use of my rail supports. Fig. 2 is an enlarged cross-sectional view taken on line 2—2 of Fig. 1. Fig. 3 is a cross-sectional view taken on line 3—3 of Fig. 2.

In all the views the same reference characters are employed to indicate similar parts.

It has heretofore been the prevalent custom, in railway track construction to use cross-ties of substantially uniform size, or of substantially equal load supporting area along all parts of the track. These ties are usually of insufficient width, properly to take care of the imposed loads, especially at the meeting ends of the rails, the weakest parts of said road structure. To strengthen the rails at their meeting ends the use of splice bars, held together by splice bolts, taking through said bars and the webs of the rails, have been resorted to in an effort to strengthen these weaker parts, to maintain the track in alignment and uniformly unyielding. Such expedience necessitates a large part of the load to be carried by the splice bars and the bolts. The imposed loads at these points produce stretching or elongation of the splice bolts and undue wear upon the contacting edges of the splice bars, resulting in loosening of the nuts and general inefficiency of such joints. The unceasing vigilance and inspection necessary to

maintain the nuts tight upon the bolts, at all of the joints, in order that such joints may not become a menace to the safety of the moving trains along the tracks is too well recognized to require further comment. It is to overcome these objections and frailties of track construction for which my present invention was designed.

If the rails be properly and sufficiently supported at their meeting ends, so that they will remain uniformly in horizontal alignment, during the passing of the loads thereover, it will not be necessary to reinforce the rails at their meeting ends with splice bars, bolts and such other contrivances. Proper devices, however, should be provided to maintain the gage; to take the lateral thrust at curves; to prevent creeping, and to provide sufficient bearing surface between the rails and cross ties.

In connection with proper and sufficient support for the rails at their meeting ends, consisting of a tie and an extended sub-base therefor, substantially as disclosed in my Patent No. 1,060,373, dated April 29, 1913, I provide a special rail fitting including in one device, all of the features above enumerated.

In the construction of a track for railway purposes, I prefer to place one of my large sub-base ties 10, having a supporting area substantially equal to 3 or more of the ordinary ties, immediately under the meeting ends of adjoining rails 11—12 and 11'—12' as shown in Fig. 1, and intermediate these sub-base ties, I place the usual ties 14, as they are employed in ordinary track construction. By this means I have a very large weight supporting area immediately below the joints of the rails which is capable of supporting the rails in perfect alignment during the time when the loads, such as heavy railroad trains are passing over the joints. If there be no vertical deflection at the joints of the meeting rails it will be unnecessary to apply supports in the nature of splice bars, fish plates or the like to take and maintain the imposed burden, as the enlarged cross ties or sub-bases 10, will distribute the weight over such a large area as to render this portion of the track stanch and vertically stable. Upon the sub-base 10 are placed the ordinary, preferably wooden, cross ties, 15, between the flanges 16 and 17 and I retain the ties 15 in place by means of bolts 18, to prevent

longitudinal displacement of the tie with reference to the sub-base.

At the meeting ends of the rails, and immediately superposed above the tie 15, are placed the fittings 19. The portion 20 constituting the rail brace is preferably placed upon the outside of the track. This fitting or chair is, preferably, of width equal to the width of the tie 15 and is provided with integral projecting studs 21 to project into or through the usual perforations or orifice in the webs at the ends of the rails. The part 20 constitutes a rail brace, and being placed on the outside of the rail, it is adapted to take the thrust due to the shifting of the load in going around curves, the stress being impressed upon the rails by the flanges 22 of the wheels 23. The studs 21 prevent creeping of the rails and have a tendency to maintain them in their proper positions on the ties. The part 24 comprises the tie plate, or base, for distributing the weight from the rail upon the upper surface of the tie, and while I have shown the part 24 to extend only midway under the rail, it is within the contemplation of my invention to have this part extend as shown or to the full width of the rail, or beyond, if desired.

A fitting 25 is placed on the inside of the rail, and in the illustration shown in Fig. 3, the parts, consisting of the rail brace 20 and the studs 21-21' are not included, in the fitting 25, as a rail brace, located on the inside of the rail, would in most cases be superfluous or unnecessary.

My invention, however, contemplates the use of two devices, 19, one upon either side of the rails at the same joint in which event the studs 21-21' from each fitting would extend only half way through the web 12' of the rails instead of extending entirely through the webs as shown in Fig. 3. The fitting 25 may underlie a portion of the base of the rail, and overlie a portion, as shown, to an extent desired. The rail is held in vertical position by the coöperation of the fitting 25 and the rail brace, 20 to withstand the lateral thrust that may be imparted to the inner side of the rail surface. I prefer to hold the fittings 19 and 25 on the tie 15 by means of threaded lag screws 26, that are threaded into the ties 15.

The perforations in the parts 19 and 25 for the screws are sufficiently large to per-

mit considerable latitude of movement 55 thereof, with respect to screws 26, so that any expansion of the parts 19 and 25 will not operate, through the instrumentality of the screws, to split the ties.

I have made the surfaces 19' and 25' of 60 the respective devices flat, as shown, so that in the event that the wheels 23 should leave the track the flanges will have a flat surface upon which to run, without tearing off the heads of the bolts 26, which would occur if 65 these surfaces were angular.

The rail supporting structure, 19, may be used quite independently of the sub-base 10 but the results that would follow would not be so satisfactory. It is also evident that 70 other means for extending the bearing area immediately under the joints may be employed than that shown and used in conjunction with my rail brace support 19 but the best results may be obtained by using the 75 device as illustrated in the drawings.

Having described my invention what I claim, with a view and desire to secure by Letters Patent of the United States is:

A rail support for the meeting ends of 80 rigidly supported railway rails, comprising a tie plate base portion, to underlie the rails; an angular brace portion, extending upwardly from the plate, having on its upper edge a bead adapted for engagement under 85 the head of the rail and a second bead below the first for engagement with the web of the rail at its juncture with the base, the portion of the brace between the two beads being offset from contact with the web of the rail; 90 laterally extending studs, integral with the brace projecting from the offset portion thereof and adapted to engage the usual orifices provided in the webs of the rails, said 95 brace portion at its longitudinal center adjacent the juncture of the rails being transversely enlarged and pocketed at its inner face; and means, for securing the edge portions of the rails to the tie upon the side opposite to that upon which said fitting is 100 placed.

In testimony whereof I hereunto set my hand in the presence of two witnesses.

ALFRED L. STEVENS.
